UNITED STATES PATENT OFFICE.

NORMAN B. LAWSON, OF MUSKEGON, MICHIGAN.

SWIMMING ATTACHMENT.

SPECIFICATION forming part of Letters Patent No. 760,881, dated May 24, 1904.

Application filed January 15, 1904. Serial No. 189,216. (No model.)

To all whom it may concern:

Be it known that I, NORMAN B. LAWSON, a citizen of the United States, residing at Muskegon, in the county of Muskegon and State of Michigan, have invented certain new and useful Improvements in Swimming Attachments, of which the following is a specification.

The object of this invention is to provide means attached to the arms and legs of a person which will assist the wearer in swimming—that is, attain greater speed than is possible without such devices.

In the accompanying drawings, Figure 1 is a perspective view of a figure with my improvements in connection therewith in which the flukes are open. Fig. 2 is a similar view in which the flukes are closed. Fig. 3 is a plan view, partly in section, of my improvements detached from the suit and applicable to the legs of the wearer. Fig. 4 is a plan view, partly in section, of my improvements detached from the suit and applicable to the arms of the wearer.

In the accompanying drawings I have shown my improvements in connection with a suit; but it is evident that they may be attached directly to the arms and legs of the wearer without departing from the scope of my invention.

The suit 1 is designed to be waterproof and entirely inclosing the body of the wearer, serving to keep the body warm and dry.

My improved attachment comprises in this instance a tubular section 2, having a portion 3, turned at substantially right angles to the tubular portion. To the tubular portion 2 are connected a series of clamps 4, having perforated ears 5. To each clamp is pivoted a fluke 6, having its face extending transverse to the length of the tubular portion. The tubular sections 2 are connected to the arm and leg receptacles of the suit by the straps 7, the portion 3 of the sections secured to the legs pass under the feet and the portion 3 of the sections secured to the arms located within reach of the hands. The flukes are con-

nected by a rod 8, and the rod connecting the flukes of the leg-sections has a link 9 pivotally connected thereto, and to the other end of the 50 rod is pivotally connected a bar 10, extending through a slot 11 in the main tubular portion 2, its other end pivoted to the clamp 12, connected to the section 3. A foot-rest 13 is supported by the bar 10.

A link 14 has a pivotal connection with the rod 8, connecting the flukes of the arm-sections, and a bar 15 has one end pivoted to the link 14 and its other end pivotally connected to the clamp 16, connected to the section 3. 60 A handhold 17 is supported by the bar 15. The bar coming in contact with the end of the slot 11 and the bar 15 resting against the end of the tubular section 2 will act as a stop to the opening movements of the flukes. The 65 forward movement of the arms and legs will permit the flukes to fall back and present the least obstruction to their forward movement. As the arms and legs are moved rearward the flukes will be forced open and hold the arms 70 and legs at rest, while the body is forced ahead. The operation is repeated each time the arms and legs are moved. By this arrangement the person having my attachment connected to his arms and legs will attain greater speed 75 through the water than without them, and in cases of disaster on the water near the shore he may be able to reach the shore with a rope before becoming exhausted or frozen.

The suit will protect the wearer, which will 80 allow him to stay longer in the water than without it.

I claim as my invention—

1. A swimming attachment, comprising a bar, a fluke having a pivotal connection with 85 the bar, and means for positively opening the fluke.
2. A swimming attachment, comprising a bar having a portion extending substantially at right angles to its length, a fluke having 90 pivotal connection with the bar, and connections between the fluke and bar whereby the fluke may be positively opened.
3. A swimming attachment, comprising a

bar, a series of flukes having pivotal connection with the bar, a rod connecting the flukes and connections between the rod and bar whereby the flukes can be positively opened.

5 4. A swimming attachment, comprising a bar, a series of flukes having pivotal connection with the bar, a rod connecting the flukes,

a linked connection between the rod and bar, and a plate supported by one of the links.

NORMAN B. LAWSON.
